RECOIL MECHANISM

Clarence E. Simpson, Springfield, Mass.

Application January 3, 1946, Serial No. 638,903

5 Claims. (Cl. 89—177)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to a recoil mechanism for larger caliber firearms than can be fired from the shoulder without auxiliary recoil absorbing means.

In firing large caliber firearms such as mortars, which are designed to operate from the shoulder, there is always the problem of dissipating a sufficient proportion of the energy of recoil so that the residual energy can be safely or comfortably absorbed by the operator. Various methods employed for reducing the residual energy of recoil have met with indifferent success, some having failed to reduce the energy of recoil to within practical limits, some having been too complicated, and some having been dependable in operation.

It is therefore the purpose of this invention to provide a recoil mechanism that will dissipate a considerable proportion of the energy of recoil, that will be reasonably simple, and that will be dependable in operation.

The specific nature of the invention as well as other objects and advantages thereof will clearly appear from a description of a preferred embodiment as shown in the accompanying drawings in which:

Fig. 1 is a fragmentary right side elevational view of the shoulder mortar partly broken away to show the firing mechanism.

Fig. 2 is an enlarged detail view of the firing mechanism shown in the cocked position.

Fig. 3 is a longitudinal sectional view of Fig. 1 taken along the line 3—3.

Fig. 4 is an enlarged cross sectional view taken along the line 4—4 of Fig. 2.

The invention is illustrated in connection with a mortar consisting essentially of a housing assembly in which is slidably engaged a mortar tube and breech cap arranged to recoil against a return spring. A gas-actuated brake is provided in the breech cap and operates against the inner wall of the housing.

For the purposes of illustration, this invention will be described primarily in its relation to ordnance pieces, such as mortars, which have open firing chambers. However, it is to be understood that the apparatus and the function thereof as herein described are, with only minor changes, equally adaptable for other types of mechanism in which fluid pressure is arranged to actuate a braking mechanism for checking the travel of an element.

2

The assembled housing comprises a cylinder 1, a rearwardly extending cylinder extension 10, an adapter-bushing 5 which is provided and adapted for securing cylinder extension 10 to the cylinder 1, and a forwardly extending guide sleeve 24 threadably secured to cylinder 1.

Cylinder 1 is provided with a plurality of circumferential reinforcing ribs 2, longitudinally spaced and arranged as shown in Fig. 1. A hammer slot 4 is provided in the underside for cooperation with a hammer as will be shown later.

The adapter-bushing 5 is threadably engaged to the rearward end of cylinder 1 and to the forward end of cylinder extension 10 and is arranged to secure cylinder 1 and cylinder extension 10 in fixed coaxial relation. A set screw 3 is provided for securing cylinder 1 and cylinder extension 10 against rotational movement relative to each other. An annular bearing ring 6 is provided inside of and integral with adapter-bushing 5 for a purpose to appear later. Adapter-bushing 5 is provided with recesses 7 for lightening purposes.

25 An adapter-cap 13 is provided for securing cylinder extension 10 to a shoulder rest 18. This adapter cap 13 is threadably engaged to cylinder extension 10. An annular recess 15 is provided in the forward or inside face of adapter-cap 13 for a purpose to appear later, and an axial recess 16 is provided for lightening the cap. The shoulder rest 18 is secured by any convenient means to the back of adapter-cap 13. The shoulder rest 18 is composed of a back plate 19 and a cushion 20 as shown in Fig. 1. A set screw 21 is provided for securing adapter cap 13 in fixed relation to cylinder extension 10.

Guide sleeve 24 is threadably secured in the forward end of cylinder 1 and is locked in fixed relation therewith by a set screw 25 provided for that purpose. A bearing 26 is provided in the front end of guide sleeve 24 and a radially disposed cylindrical key 28 is provided in the underside of sleeve 24 adjacent the front end, all for a purpose to appear later.

45 A tube 30 is threadably secured to a breech cap 35 and is provided with a longitudinal key-way 31 for cooperation with the key 28. In assembled relation, tube 30 is slidably engaged in bearing 26 of guide sleeve 24 and cylindrical key 28 is 50 slidably engaged in key-way 31 in the tube 30 thereby preventing tube 30 from rotational movement in guide sleeve 24.

Breech cap 35 is in the general form of a cylindrical cup, the side wall 36 being threadably 55 engaged onto tube 30 and secured thereto by

staking. The base 37 of breech cap 35 is substantially of greater diameter than the remainder of cap 35 as shown in Fig. 3, and is provided with a plurality of spaced chordal slots 38 (two diametrically opposite slots of equal depth in the preferred embodiment). A cylindrical recess 39 is radially provided in the breech cap 35 in communication with the center of each chordal slot 38. Apertures 40 are provided in base 37 to connect cylindrical recesses 39 to the interior of tube 30 which serves as the firing chamber 41 of the mortar. A brake shoe 44 in the form of a chordal segment is adapted to slidably fit in each chordal slot 38 in breech cap 35. A piston 45 is slidably inserted within a suitable hole provided in each brake shoe 44. The head of each piston 45 rests within respective cylindrical recesses 39. The arcuate face 47 of brake shoe 44 is arranged to be concentric with the inner surface of cylinder 1. Brake shoe 44 and piston 45 are arranged with relation to breech cap 35 so that gas pressure developed in firing chamber 41 is transmitted through aperture 40 to piston 45 thereby forcing brake shoe 44 against the inner surface of cylinder 1.

An axial firing pin hole consisting of an aperture 50 and an orifice 51 extends through breech cap base 37. A boss 52 is provided on the rearward face of breech cap base 37 coaxial with firing pin aperture 50. A screw collar 53 is secured to boss 52 by suitable threads and is provided to maintain a firing pin 55 within firing pin aperture 50. A firing pin spring 56 is provided for resiliently maintaining firing pin 55 in a normally retracted position. A longitudinal cam cut 42 is provided underneath breech cap 35 for a purpose to be shown later.

A breech-cap extension sleeve 60 with terminal bearing ribs 61 and 62 is attached to the rearward face of breech cap 35 by pins 63 so that a hammer slot 64 provided in the bottom of sleeve 60 will be maintained in longitudinal alignment with cam cut 42 in the breech cap 35.

A bushing 68 is provided in the rearward end of breech-cap extension sleeve 60, the bushing having a longitudinal extension 69 arranged coaxial with cylinder 1. Another tubular spring guide 70 is threadably secured on extension 69 and extends rearwardly to be slidably engaged in annular bearing ring 6 in adapter-bushing 5. Apertures 71 are provided in bushing 68 to permit free flow of air therethrough, and cushion 72 is provided on the rearward face of the bushing for a purpose to be shown.

A recoil spring 75 is provided for assembly between bushing 68 and adapter-cap 13, lying inside outer spring guide 70 as shown in Fig. 3. The rearward end of spring 75 is engaged in the annular recess 15 in adapter cap 13. Also an inner tubular spring guide 77 is secured in annular recess 15 inside of spring 75 and extends forward to a point slightly within the rearward end of outer guide 70.

Since breech-cap extension sleeve 60 is pinned to breech cap 35, which in turn is staked to the tube 30 and the tube is held in angular alignment with guide sleeve 24 by engagement of cylindrical key 28 in key-way 31 in the tube, and since guide sleeve 24 is secured in position in cylinder 1 by means of set screw 25, it follows that hammer slot 4 in cylinder 1 and hammer slot 64 in breech cap extension sleeve 60 and cam cut 42 in breech cap 35 are maintained in longitudinal alignment thereby at all times.

A pistol grip 80 is provided on the underside of cylinder 1, together with a trigger 81 and trigger mechanism of conventional type adapted to the particular application. A hammer 82 is pivotally mounted just below the forward portion of hammer slot 4 in the cylinder and is arranged so that in the cocked position it is locked horizontally below the slot by a sear 84. Hammer 82 is arranged to be actuated by a torsion spring 83 for upward pivoting movement so as to strike firing pin 55 when sear 84 is depressed by pulling trigger 81.

In operation the firing mechanism is cocked by forcing the mortar tube 30 inwardly until hammer 82 is forced downward to a horizontal position by the camming action of cam cut 42 in breech cap 35. A mortar shell (not shown) is then placed in the mortar tube 30 and the mortar held to the shoulder and aimed as desired. When the trigger 81 is pulled back, hammer 82 is released and is pivoted up through hammer slots 4 and 64 in cylinder 1 and breech cap extension sleeve 60 respectively to strike firing pin 55 which is thereby driven forward to fire the mortar shell (not shown).

The high gas pressure developed in firing chamber 41 forces the mortar tube and breech cap assembly rearwardly against the force of recoil spring 75, causing bushing 68 and spring guide 70 to move rearwardly. Spring guide 70, being outside of spring 75, slides rearward through bearing ring 6 in adapter-bushing 5 in telescoping relation with respect to inner spring guide 77, cushion 72 engaging the forward face of adapter-bushing 5 at the end of the stroke to cushion the impact thereon.

At the same time, the entrapped gases expand through apertures 40 in breech cap 35 into radial cylindrical recesses 39 and exert pressure in a radial direction outwardly against pistons 45, thereby forcing brake shoes 44 against the wall of cylinder 1 to cause a large quantity of frictional resistance which will be proportional to the product of the gas pressure developed and the period of application. As soon as the mortar shell has left mortar tube 30, the gas pressure is destroyed, hence the brake shoes 44 are no longer maintained in frictional contact with cylinder 1, so that on the counter-recoil stroke the tube and breech cap assembly move forward with a minimum of frictional resistance.

When breech cap 35 moves rearward, the hammer 82 is engaged in cam cut 42 in the breech cap and is thereby cammed downward to a horizontal position, being caught and held in that position, clear of the breech cap 35 by engagement with sear 84 until again released through action of trigger 81.

While the invention is illustrated in connection with a shoulder mortar, it is to be distinctly understood that the invention is equally applicable to firearms of a size greater than can be operated manually, including all sizes of firearms in which recoil energy has to be dissipated by auxiliary means.

It is thus apparent that this invention provides a means whereby a large quantity of recoil energy can be frictionally dissipated during the recoil stroke, such dissipation being directly proportional to the magnitude and duration of the gas pressure; the pressure and hence the friction being essentially eliminated as soon as the shell leaves the mortar tube, so that the counter-recoil stroke is free from the retarding action of such energy dissipating means.

I claim:

1. A firearm comprising in combination, a housing, a tube member slidably mounted in said housing, a breech cap secured on one end of said tube member, said tube member defining a firing chamber, said breech cap having a chordal slot therein and a radially disposed recess adjoining the center of said chordal slot, said recess communicating with said firing chamber, and a brake shoe having an arcuate outer bearing surface, said brake shoe having an opening therein, a piston disposed within said opening, said brake shoe and said piston being slidably mounted within said chordal slot and its adjoining radial recess respectively, said brake shoe and said piston being constructed and arranged so that gas pressure developed in the firing chamber upon the discharge of a powder charge directly actuates said piston and said brake shoe in a radial direction to frictionally engage said housing and thereby resist the relative sliding movement of said tube member within said housing.

2. A firearm comprising in combination, a housing, a tube member slidably mounted in said housing, a breech cap secured on one end of said tube member, said tube member defining a firing chamber, said breech cap having a plurality of equi-angularly-spaced chordal slots therein and a radially disposed recess adjoining the center of each chordal slot, each of said recesses communicating with said firing chamber, and a plurality of brake shoes, each of said brake shoes having a piston associated therewith, each of said brake shoes and said piston being slidably mounted within a chordal slot and its adjoining recess respectively, each of said brake shoes and said piston being constructed and arranged so that gas pressure developed in said firing chamber upon the firing of a powder charge directly actuates said piston and brake shoe in a radial direction to frictionally engage said housing and thereby resist the relative sliding movement of said tube member within said housing.

3. A shoulder mortar comprising in combination, a housing, a mortar tube, a breech cap secured on one end of said mortar tube, said mortar tube and said breech cap being slidably mounted in said housing and jointly defining a firing chamber, said breech cap having a pair of oppositely disposed chordal slots therein and a radially disposed cylindrical recess adjoining the center of each chordal slot, each of said cylin-

drical recesses communicating with said firing chamber, and a pair of brake shoes, each brake shoe having a piston associated therewith and being slidably mounted within one of said chordal slots and its adjoining recess respectively, each brake shoe and said associated piston being constructed and arranged so that gas pressure developed in said firing chamber upon the firing of a powder charge directly actuates said piston and brake shoe outwardly in a radial direction to frictionally engage said housing and thereby resist the relative sliding movement of said mortar tube and breech cap within said housing.

4. A firearm comprising in combination, a housing, a tube member slidably mounted in said housing, a breech cap secured on one end of said tube member, a brake member provided in said breech cap, said brake member having a piston associated therewith, said brake member being operable by said piston to frictionally resist the relative sliding movement of said tube member with respect to said housing, and means for directing gas pressure developed in said tube member upon the firing of a powder charge against said piston for actuation thereof.

5. In a firearm comprising in combination, a housing, a tube member slidably mounted in said housing, a breech cap secured on one end of said tube member, said breech cap having a chordal slot, a brake member slidably mounted in said chordal slot, said brake member having a piston associated therewith, said brake member being operable by said piston to frictionally resist the relative sliding movement of said tube member with respect to said housing, and means for directing gas pressure developed in said tube member upon the firing of a powder charge against said piston for actuation thereof.

CLARENCE E. SIMPSON.
